[57] CLAIM

The ornamental design for a liner for spent nuclear fuel pools, substantially as shown.

DESCRIPTION

FIG. 1 is a reduced perspective view of a liner for spent nuclear fuel pools showing my new design;

FIG. 2 is a top plan view;

FIG. 3 is an end elevational view;

FIG. 4 is a side elevational view;

FIG. 5 is a bottom plan view; and
FIG. 6 is an enlarged sectional view taken in the direction of the arrow on line 6—6 of FIG. 1.
